VENDING MACHINE

Ludwig Kegel, Neustadt (Schwarzwalde), Germany

Application November 2, 1933, Serial No. 696,435
In Germany November 5, 1932

15 Claims. (Cl. 194—69)

This invention relates to vending machines, and has special reference to a machine for vending articles of various sizes and shapes and at various prices.

5 Most vending machines are designed to vend articles of regular size and shape or to vend a given quantity of small articles such as nuts or confectionery and, in such machines, it is usual to have a storage compartment or magazine in which all of the commodity to be sold is held.

One important object of the present invention is to provide an improved form of vending machine, wherein each article or package to be sold is held in an individual compartment, access to 15 the several compartments being selectively obtainable.

A second important object of the invention is to provide a novel form of vending machine having a series of compartments each normally held 20 against opening by an individual latching mechanism.

A third important object of the invention is to provide a novel means for preventing the opening of more than one compartment at a time, the 25 means being so arranged that the operation of one compartment latching mechanism to unlatch a compartment prevents operation of the remaining latching mechanisms.

A fourth important object of the invention is 30 to provide a novel arrangement of compartment latching mechanisms wherein accidental relatching of a compartment after the same has been unlatched is prevented.

A fifth important object of the invention is to 35 provide a single coin control of novel character common to all of said latching mechanisms.

It is common in vending machines to so construct such machines that they are permanently set to work with the deposit of a definite 40 amount in coins, either by a single coin of definite value or by a plurality of coins, the sum of the values of which amounts to a definite value.

A sixth important object of the present invention is to provide a novel form of coin control device for such machines which may be set to operate by the insertion of one or more coins within 45 the sales value capacity of the machine. Thus, if the maximum sales value capacity of the machine is twenty-five cents, the machine may be set to operate by the insertion of from one to five five-cent pieces, according to the value of the article being sold.

A seventh important object of the invention 50 is to provide a novel setting mechanism for the

coin control including a series of interchangeable setting bars.

It is desirable in such machines that for the purposes of changing the commodities, filling and replenishing the machine with commodities, the compartments for the goods sold may be opened by an attendant without the deposit of coins. 5

An eighth important object of the invention is to provide a novel releasing device for the coin control of the machine whereby opening of the 10 money receiving compartment or drawer will effect release of the coin control in such manner that the commodity compartments may be successively opened.

A ninth important object of the invention is to 15 provide novel means of assembly and disassembly of the machine wherein closing and opening of the money drawer or compartment controls the disassembly of the machine.

With the foregoing and other objects in view, 20 the invention consists in the details of construction and in the arrangement and combination of parts to be hereinafter more fully set forth and claimed.

In describing the invention in detail, reference 25 will be had to the accompanying drawings forming part of this application, wherein like characters denote corresponding parts in the several views, and in which—

Figure 1 illustrates a side elevation, partly in 30 diametric section, of one form of machine constructed in accordance with this invention;

Figure 2 illustrates a partial plan view thereof with certain parts broken away to show a certain latch beneath the broken parts; 35

Figure 11 illustrates an assembly view of a set of setting bars used herein;

Figure 12 illustrates a front elevation of a modified form of the machine; and

5 Figure 13 illustrates an end elevation of the modified form.

In the form of the invention as shown in Figures 1 to 11, there is provided a base plate 10 having an upwardly projecting and centrally disposed boss 11 provided with a central aperture 12. Revolubly fitted in the boss 11 is a stub-shaft 13 which is fixed centrally to the underside of the bottom plate 14 of the main casing of the machine. This stub-shaft 13 is held from withdrawal from the boss 11 by means of a washer 15 secured on the lower end of the stub-shaft by a screw 16, said washer being of greater diameter than the opening 12 so that its peripheral portion underlies the metal of the base 10 around the opening 12. The upper face of the base adjacent its periphery forms a flat annular surface 17 and the bottom plate 14 is provided on its underside with an annular rib 18 which is in opposed spaced relation to the surface 17. In the under surface of this rib is formed an annular groove 19, preferably of V-shape, and bearing balls 20 rest on the surface 17 and are held in the groove 19. A flange 21 depends peripherally from the plate 14 and to this flange is secured, by welding or other suitable means, the lower part of a money drawer housing 22 having an opening 23 at one side thereof. A money drawer 24 having a curved coin holder 25 is mounted on the plate 14 to slide in and out through the opening 23. A drawer pull 26 is carried on the front of this drawer to enable it to be pulled out when desired and the drawer is normally locked by an ordinary lock schematically shown at 27. A stop 28 is screwed up through the plate 14 and, when 40 the drawer is pulled out, is engaged by the lower part of the back wall of the drawer so as to limit outward movement of said drawer.

The upper end of the drawer housing is provided with an outwardly extending flange 29 whereon rests a reinforcing angle 30 suitably secured to the casing 22. On the angle 30 is secured a cooler casing for containing ice or other cooling medium and this casing is of annular formation having a frusto-conical inner wall 31 and an outwardly extending and upwardly curved bottom and outer wall 32. The upper edge of the wall 31 is provided with an inwardly extending flange 33 from the inner edge of which depends the side wall 34 of the lower section of a mechanism housing. A bottom 35 closes the lower end of this lower section. The cooler compartment is closed on top by an annular plate 36 which is coterminous at its inner edge with the wall 34, thus resting on the flange 33 to which it is suitably secured. The outer edge of the wall 32 is provided with an outwardly extending flange 37 around which the outer part of the plate 36 is bent to hold said plate 36 in position. Obviously, suitable means of access to the cooler compartment will be provided, but it is not deemed necessary here to show such means. Resting on the inner peripheral portion of the plate 36 is a series of arcuate spacer strips 38. Alined with the side wall 34 of the lower mechanism housing is the side wall 39 of an upper mechanism housing and this side wall 39 has an outwardly extending flange 40 at its lower end, which flange rests on the spacers 38 and is secured thereto by screws 41. The upper housing is closed at its top by a cover 42.

The mechanism housing is preferably cylindrical in form and extending radially from this housing is a series of vertical partitions 43 which have their bottom edges resting on the plate 36. Guides 44 are secured to the plate 36 in pairs to receive the lower edge portions of the plates 43 and hold them properly spaced. Similar pairs of guides 45 are mounted on the wall 39 and receive the inner edges of the plates 43 between them to hold these plates in vertical positions. 10 These partitions thus form a series of segmental compartments and a cover plate 46 of annular form rests on top of these partitions to constitute a top for the compartments. Preferably this cover plate is, like the partitions, of glass. The upper 15 housing projects above the cover plate 46 and fitted on this housing is an annular keeper band 47 having an outwardly extending flange 48 on its lower edge which engages over the cover plate and holds it in position. The band 47, intermediate its upper and lower edges, is provided with an annular bead 49 forming a channel confronting the mechanism housing. In each of the compartments is slidably mounted a drawer having a bottom 50 and a front wall 51 which, when the 25 drawer is pushed in, closes the outer end of the respective compartment. A drawer pull 52 is provided on each wall 51 to enable ready manipulation of the drawer. The inner end of each bottom 50 is provided with an inwardly extending tongue 53 which passes into the mechanism housing between adjacent spacers 38 and this tongue is provided with an opening or eye 54 normally located within the mechanism housing.

Within the housing is a frame which supports 35 the coin controlled mechanism and the parts associated therewith. This frame consists of a frame base 55 which rests on the housing bottom 35 and is provided with a plurality of openings 56 adjacent its periphery. The openings 56 receive 40 the lower reduced ends of lower post sections 57 and screws 58, having heads of greater diameter than the openings 56, are screwed up through these openings to hold the posts in position. The housing bottom 35 is provided with suitable openings to allow projection of the screw heads there-through. The upper ends of the posts 57 are reduced and fit into openings 59 in an annular lower frame ring 60. Intermediate post sections 61 are provided with reduced screw-threaded ends 50 62 and the lower screw-threaded ends pass through the openings 59 into the upper ends of the lower post sections 57, these being provided with screw-threaded axial bores to receive such threaded ends. Resting on the bodies of the post sections 61 is an upper annular frame ring 63 provided with openings 64 wherethrough pass the upper screw-threaded ends 62. Upper post sections 65 have their lower ends bored and threaded to screw onto the upper ends 62 and the upper ends of these sections 65 are reduced to fit in openings 66 in a frame top plate 67 where they are held by screws 68. By this means the entire frame is rigidly held together while, when necessary, the parts may be readily assembled and disassembled.

The rings 60 and 63 and the frame bottom 55 fit closely in the mechanism housing so that the frame is thus held in proper position in the housing. However, by unscrewing the screws 41, the upper housing section may be lifted from the lower and the frame, with all parts carried thereby, lifted out of the lower housing section.

A series of openings 69 are formed adjacent the periphery of the cover 42 and a second series of 75

openings 70 are formed in the plate 67 in alignment with the openings 69. The centers of the openings 69 and 70 lie in the vertical median planes extending radially through the compartments. Thus there is an opening 69 and an opening 70 for each compartment. For each compartment there is a drawer releasing plunger which consists of an upper section 71 and a lower section having a body 72 slidably mounted in a respective set of the openings 69 and 70. The upper section 71 has a push button 73 on its top end and a threaded extension 74 on its bottom end, this threaded extension being screwed into the body 72 to unite the two sections. By this arrangement the lower section may be pushed up through the openings 70 and 69 and the upper section be then screwed on the lower to assemble the parts. An extension 75 is formed integral with the body 72 and is in the form of a flat bar extending downwardly from the lower end of the body 72 and offset outwardly in a direction radial of the mechanism housing. The lower end of this extension is rabbeted on its outer corner to form a tail 76 which is received in a radial slot 77 formed in the upper frame ring. For each of these extensions, which may be termed presser bars, there is provided a coiled tension spring 78 which has its lower end engaged on a pin 79 fixed in the presser bar and its upper end engaged on a pin 80 extending radially from the plate 67. Thus the plungers are constantly urged to raised positions. Each tail 76 is provided with a laterally extending lug 81 which lies below the frame ring 63 and engages with the under side of said ring and forms a limit stop to limit the lift of the plunger under the influence of the spring 78. Slots 82 are formed in the lower frame ring 60 aligned below the slots 77 and in the frame bottom 55 are slots 83 which are in vertical alignment with the slots 82. In each set of slots 82 and 83 is mounted a latch bar. This latch bar has an upper end 84 mounted in the slot 82 and a lower end 85 mounted in the slot 83. The lower part of the upper end 84 is enlarged to form shoulders 86 which form limit stops preventing this latch bar from rising beyond a certain limit and from this enlarged portion the bar extends downwardly and inwardly to provide an inclined cam edge 87 on its outer edge. The lower end of the inclined portion extends forwardly to the upper end of the portion 85. Projecting outwardly from the upper part of the portion 85 is a latch lug 88 having a beveled edge 89. For each of the latch bars there is provided a coiled tension spring 90 which has its lower end engaged on a pin 91 projecting from the latch bar and its upper end engaged on a pin 92 projecting inwardly from the lower frame ring 60. Thus the latch bar is normally held raised and, when in this raised position, the nose 60 of the latch lug 88 enters the opening 54 from below. It is to be noted that the lower end of the tail 76 of the presser bar is vertically spaced above the top of the latch bar and that the lateral lug 81, besides forming a stop, has the further function of broadening the contact area whereagainst the latch bar may engage when the presser bar is pushed down. This part of the apparatus, including the plunger and latch bar, forms the means for holding the drawers from opening movement and it will presently be seen that the plunger is coin controlled so that it cannot be effectively operated until released by the deposit of the proper coins. However, for the purpose of explaining the operation of this part of the device, it may now be assumed that the plungers are free

to move down. If now a given plunger be depressed against the action of spring 78, its lower extremity moves downwardly and engages the upper extremity of the latch bar. Further depression of the plunger depresses the latch bar and the nose of the latch lug is first moved downwardly until it is freed from the eye 54. As this is down, the inclined cam edge engages the inner edge of the tail 53 whereupon the drawer is pushed slightly open so that release of the plunger will not effect reengagement of the latch lug nose in the eye 54. The plunger may now be released and the drawer pulled out so that its contents can be removed. 5

In order to prevent a second plunger from being depressed until the first has been released, the following arrangement is used. Mounted on the frame ring 63 is a ring 93 which has at its outer periphery an upstanding flange 94. Formed in the bottom of this ring adjacent its outer periphery is a slot 95 wherein is slidably mounted a series of segmental bars 96 equal in number to the presser bars. The combined arcuate lengths of the bars 96 is less by the thickness of one presser bar than the full length of the slot 95. 25 For each presser bar the ring 93 is provided with a slot 97 extending from its outer periphery inwardly and the meeting ends of the segments 96 register with these slots. These meeting ends have their top corners beveled off as at 98 (Fig. 30 8). The shoulder formed by the rabbet at the lower end of the presser bar normally lies above these meeting ends but, when the presser bar is depressed, this shoulder is forced in between two of the segments 96, thereby crowding the others 35 together so that they are held in contact and cannot be spread to permit depression of a second presser bar until the first is released. As will be seen from what follows, if a presser bar is depressed to effect unlatching of a drawer and 40 is then released, all bars will be locked against further effective depression until a further coin deposit takes place.

In the construction of the coin mechanism there is provided a carrier plate 99 extending 45 vertically from the frame bottom 55 to the frame top 67 and securely fixed to these parts in a position slightly offset from the center of the mechanism housing. Extending through the upper end of the carrier plate is a slot 100. A coin receiving tube 101 has its upper end located on the side of the center of the mechanism housing opposite that on which the carrier plate is located, and extends from above the housing top 42 in a reversely curved direction so that the under or 50 rear wall of this tube is brought into alignment with what may be termed the front face of the plate 99, meaning thereby the face more remote from the center of the mechanism housing. This causes the coin tube to pass through the slot 100 and below the bottom of the slot 100 the side and rear walls of this tube are cut away to leave only the front wall. One edge of this front wall 102 is secured by screws 103 to vertically spaced spacer blocks 104 fixed to the front side of the plate 99, 65 the other edge being left entirely free. In order to partly close the gaps between the spacer lugs 104, and for other purposes presently to be described, there is mounted on the rear face of the plate 99 a series of vertically spaced stop bars 105 each secured to the plate 99 by a pair of screws 106 passing through a pair of slots 107 extending longitudinally of the stop bar and thus transversely of the plate 99. The vertical spacing of 70 these stop bars equals the diameter of the coins 75

to be used in the machine. Each stop bar is provided with a lug 108 extending through a slot 109 in the plate 99 and normally in substantial alignment with the spacers 104 although slightly projecting inwardly of the coin passage. Each stop bar is yieldably held in normal position by a coiled tension spring 110 having one end connected to a pin 111 on the stop bar and its other end connected to a pin 112 on the plate 99. When thus held, the lugs 108 are at one end of each of the slots 109 but may move outwardly of the coin path toward the other ends of said slots. Just below the plate 67 is a plate 113 which is provided with a central opening 114 for the accommodation of the coin tube and other parts so that this plate may have vertical movement. A plunger latch bar 115 has its upper end secured to this plate by a screw 116 passing through a flange 117 formed on the upper end of the bar. The shoulders formed at the bottoms of the portions 72 of the plungers by the offset arrangement of the presser bars 75 rest on top of the peripheral portion of the plate 113. Obviously, so long as the bar 115 and plate 113 remain raised, the plungers cannot be depressed. The bar 115 is guided between clips 118 secured to the plate 99 by screws 119 and is held normally raised by a coiled tension spring 120 having one end connected to a pin 121 carried by said bar while its other end is connected to a pin 122 carried by the plate 99. One edge of the bar lies adjacent the stop bars 105 and this edge is provided with notches 123 abruptly shouldered at their upper ends and receiving the adjacent ends of the respective stop bars. The lengths and arrangement of these notches are such that the plunger latch bar 115 may be depressed for a distance corresponding to the distance between the presser bar 75 and the latch bar 84. This is so because, as will be presently understood, initial movement of the bar 115 effects the first movement to release coins held in the coin passage. Beneath the free edge of the plate 102 (see Fig. 9) is positioned a coin release bar 124 which is secured to the plate 99 by a screw 125 passing through a slot 126 formed in an extension or lug 127 projecting from the outer edge of the bar. The bar is held yieldably in its outer position by a pair of coiled tension springs 128 arranged at equal distances above and below the slot 126 and each having one end connected to a pin 129 on the bar and its other end connected to a pin 130 on the plate 99. The outer edge of this bar rests against actuating pins 131 fixed to the plunger latch bar 115 and extending through vertical slots 132 formed in the plate 99. The bar 124 has its outer edge provided with V-shaped lugs or cams 133 which normally lie just below the pins 131.

While provision is made for rendering certain of the stop bars inactive, as will be presently explained, we may consider for the present that all of the stop bars are active and that a number of coins have been dropped in the coin tube equal in number to the stop bars so that each coin is engaged on one side by a lug 108 and on its other side by the coin release bar 124. Now a plunger may be depressed whereupon, during the initial part of its movement, the plate 113 will move downwardly and carry with it the plunger latch bar 115 and pins 131. The pins 131, engaging the cams 133, force the coin release bar inwardly and the coins C press against the lugs 108 and move the stop bars 105 to clear the notches 123. At this time, the upper ends of notches are aligned with the upper edges of the stop bars so that slight

further depression of the plunger brings unnotched parts of the bar 115 opposite the ends of the stop bar. As the pins 131 move over the high spots of the cams the coin release bar moves outwardly, but the lugs 108 do not now move with the bar since the stop bars bear against unnotched parts of the plunger latch bar. Thus the plunger can move freely downward and at the same time the coin release bar moves outwardly so that the coins are free to drop out of the lower end of the 10 chute into the tray 25.

The following mechanism is provided to close the lower end of the coin passage or chute against the passage of coins to the money drawer prematurely. The coin chute proper terminates 15 slightly above the plate 55 which has an opening 134 and a cut off plate 135 normally lies in the space between the coin chute and plate 55. The plate 135 is held on the plate 55 for rectilinear movement by screws 136 passing through aligned 20 slots 137 formed in said plate 135 and is yieldably held in chute closing position by a coiled tension spring 138 having one end connected to a pin 139 on the plate 135 and its other end connected to a pin 140 on the plate 55. The plunger latch bar 25 is rabbeted at its lower end to provide a beveled shoulder 141 which normally lies above an edge portion of the plate 135 (Fig. 10) in such position that the beveled shoulder will, when the bar is pushed down, engage the plate 135 and push it 30 to open position, the body of the bar holding the cut off plate open during further downward movement of the plunger latch bar. The beveled shoulder 141 is normally spaced above the plate 135 so that the coins in the chute may be properly gripped by the coin release bar 124 prior to the cut off plate moving to open position.

As previously stated, the device may be adjusted to selectively lock out any desired number of stop bars 105 and thus to permit the operation 40 of the coin release with fewer than the maximum number of coins for which it is built. To this end, there is employed a series of setting bars 142 each consisting of a strip of metal having an inner straight edge 143 and an outer edge having a 45 middle part 144 offset outwardly from a lower part 145 and connected thereto by an inclined portion 146. These bars are furthermore each provided with a head 147. Suitable slots are formed in the housing top 42, the plates 67, 113 50 and 55 and the housing bottom 35 to permit these bars to be inserted in the apparatus and project through the mechanism housing into the drawer 24. A bar 148 crosses the upper part of the drawer and engages in a notch 149 formed in the 55 setting bar to lock the bar against removal upon the drawer being closed. The heads 147 bear suitable indicia 150 to indicate the value of the coins to be inserted. In one of these bars the offset middle part is omitted and the others have 60 the lengths of these offset middle parts graduated. The stop bars 105 have pins 151 projecting from the ends opposite those ends which engage in the notches 123 and these pins lie against the outer edge of the bar 142. Obviously, if a bar having 65 an offset middle part be inserted, the stop bars having pins engaged thereby will be moved out of engagement with the notches and only those stop bars whose pins engage the edge 145 will be active. These setting bars have a further func- 70

Mounted centrally of the plate 67 by means of a screw 152 is a lever 153 to one end of which is connected by a screw 154 a lock bar 155 held to the plate 67 by a screw 156 passing through a 75

slot 157 so arranged that a nose 158 on said bar may be protracted and retracted through a slot 159 in the casing wall to enter and be withdrawn from the channel formed by the bead 49. A screw 160 connects the other end of the lever 153 to a slide bar 161 held to the plate 67 by a screw 162 passing through a slot 163. The setting bar 142 rests against the side of the slide bar and the latter is provided with a lug 164 which is engaged by the outer edge of this bar 142 and holds the bar 161 in position to cause protraction of the nose 158. A coiled tension spring 165 has one end connected to a pin 166 on the bar 155 and its other end connected to a pin 167 on the plate 67. This spring urges the nose 158 to retracted position so that, upon withdrawal of the bar 142, the nose automatically retracts and leaves the band 47 in condition for removal as the first step in disassembling the machine when desired or necessary.

Provision is also made to render all of the stop bars inactive upon the money drawer being pulled out and, for this purpose, there is provided a camming bar 168 which extends vertically of the mechanism housing and projects downwardly through suitable openings in the bottom 35 and plate 55 to extend into the coin tray 25. This bar 168 lies flat against the stop bars 105 and is there held by means of certain of the clips 118. One edge of the bar is provided with a series of notches 169 and each stop bar is provided with a pin 170 normally resting in a respective notch. The shape of these notches is such that they each have an abrupt shoulder above the respective pin and an inclined cam edge normally below such pin. By this means downward movement of the bar 168 is limited and upward movement of the bar 168 moves all of the stop bars out of engagement with the notches 123. The rear or inner end of the coin tray 25 has an inclined floor and when the coin drawer is pulled out, this floor engages the lower end of the bar 168 and moves it upwardly, thus effecting release of the stop bars, as above noted. The release of these stop bars permits free operation of the plungers to unlatch the commodity drawers so that these may then be opened for filling the machine or removing the goods therefrom. Obviously, since the money drawer is normally locked, this can only be done by a person having a key to the money drawer.

In order to better guide the coins into the coin tray 25 an auxiliary coin chute 171 may be arranged below the opening 134 to receive coins therefrom and to deliver them to the coin tray.

In order to prevent the use of coins of less diameter than those for which the machine is designed, the inclined rear wall of the upper part of the coin chute 191 is provided with a slot 172 of such width that coins of proper size will pass thereover, while smaller coins will drop through the slot, a vertical chute 173 is arranged below the slot 172 and extends downwardly to registering openings 174 in the plate 55 and bottom 35. Below these openings is an inclined chute 175 which leads out of the machine at its lower part. By this arrangement, small coins drop through the slot 172, pass through the chutes 173 and 175 and out of the machine.

In the form of the invention shown in Figures 12 and 13, the arrangement of the machine is rectangular instead of circular, but the internal arrangements are substantially the same except, of course, that the plate 113 is replaced by a rectangular plate or grid and that the latches for the commodity drawers are alined with the re-

spective plungers and the tongues corresponding to the tongue 54 of the circular form are of proper lengths for the operation of such latches.

The operations of the various special mechanisms having been previously explained, it is believed not necessary again to give a detailed explanation of the entire operations, but it may be briefly stated that when the machine is ready for use, the commodity drawers have been loaded with the commodities to be sold, and these drawers closed. A setting bar 142 is selected such that, counting from the bottom upwardly, a sufficient number of stop bars 105 will be left active to correspond to the number of coins to be inserted in accordance with the price at which the goods are to be sold. Thus, if the goods are to be sold for fifteen cents and the coin chute is arranged to hold five five-cent pieces when fully loaded, a setting bar operating to withdraw the upper two stop bars from the notches 123 will be selected, leaving the lower three stop bars active. This setting bar is inserted and the money drawer, which has been at least partly open, is pushed shut to lock the setting bar against removal and the money drawer is locked. The machine is now ready for the sale of goods.

When it is desired to buy any of the goods, they may be observed through the glass plate 46. The purchaser drops the requisite number of coins down the coin chute where they are brought to rest in edgewise superposed position by the cut off slide 135 at the bottom of the coin chute. He now pushes down on the plunger opposite the commodity compartment selected. The initial movement of this plunger locks the remaining plungers from being pushed down and at the same time operates the bar 124 to effect movement of the stop bars 105 out of the notches 123, thus permitting further movement downwardly of the plunger. This part of the movement of the plunger releases the presser bar 124 so that the coins are not gripped thereby, causes the cut off slide 135 to be moved to open position and unlatches the selected commodity drawer and starts it outwardly. The coins will thus drop into the money drawer and the commodity drawer will be pulled out manually. The plunger may be released at any time after the commodity drawer is unlatched, whereupon the parts will be restored to normal position and no plunger can be effectively pushed down until more coins are dropped in the coin tube.

To refill empty drawers or change the commodities for sale, the money drawer is unlocked and drawn out until the camming bar 168 is raised to release all stop bars 105 from the notches 123, whereupon all the plungers are free to be pushed down one after the other to unlatch the commodity drawers successively so that they may all be opened. When the money drawer is pushed in, the camming bar drops, releases the stop bars and permits them to assume their normal positions in notches 123. Obviously, the setting bar may be changed when the money drawer is open.

When, for any purpose, it is desired to have access to the mechanism in the housing, the money drawer is unlocked and drawn out so that the setting bar may be removed. With the removal of the setting bar the nose 158 is retracted so that the ring 47 may be removed whereupon the cover plate 46 may be lifted off, the screws 41 removed and the top section of the mechanism housing lifted, with the entire mechanism, away from the rest of the device. Obviously, the commodity drawers must be opened to prevent interference

with the latch lugs 88 before the mechanism can be lifted.

I claim

1. In a vending machine having a series of compartments and closures therefor, a series of closure latches, plungers each associated with a latch to move the latch to unlocking position, plunger release means normally holding all said plungers against latch releasing movement, said release means being movable with said plungers as the latter are moved, a stop member engaging said release means to prevent latch releasing movement of the plungers, and coin controlled means for withdrawing said stop member from said release means.

2. In a vending machine, a coin control including a coin chute, a release bar extending parallel to the chute and guided for longitudinal movement, said bar having a stop notch in the edge adjacent the chute, a stop bar mounted to move transversely of the release bar to engage in and disengage from the notch, a lug on the stop bar extending into the chute at the side remote from the release bar, spring means normally holding the stop bar in engagement in said notch, a presser bar opposite said lug and spaced from the lug at a slightly greater distance than the diameter of a coin to be used in the machine, said presser bar being mounted for movement toward and from said lug, manually operable means for effecting operation of said presser bar, means for supporting a coin in position between said lug and presser bar, and means to release the supported coin upon actuation of said presser bar.

3. In a vending machine, a coin control including a coin chute, a release bar extending parallel to the chute and guided for longitudinal movement, said bar having a stop notch in the edge adjacent the chute, a stop bar mounted to move transversely of the release bar to engage in and disengage from the notch, a lug on the stop bar extending into the chute at the side remote from the release bar, spring means normally holding the stop bar in engagement in said notch, a presser bar opposite said lug and spaced from the lug at a slightly greater distance than the diameter of a coin to be used in the machine, said presser bar being mounted for movement toward and from said lug, manually operable means for effecting operation of said presser bar, a spring-held cut-off normally closing the lower end of said chute, and means on the release bar engageable with the cut-off and moving the latter to open the chute upon movement of the release bar.

4. In a vending machine, a coin control including a coin chute, a release bar extending parallel to the chute and guided for longitudinal movement, said bar having a stop notch in the edge adjacent the chute, a stop bar mounted to move transversely of the release bar to engage in and disengage from the notch, a lug on the stop bar extending into the chute at the side remote from the release bar, spring means normally holding the stop bar in engagement in said notch, a presser bar opposite said lug and spaced from the lug at a slightly greater distance than the diameter of a coin to be used in the machine, said presser bar being mounted for movement toward and from said lug manually operable means for effecting operation of said presser bar, a camming bar engageable with the stop bar to withdraw the stop bar from the notch upon movement and normally positioned to permit engagement of the stop bar in the notch, a money drawer movable between open and closed positions, means in the

money drawer engaging the camming bar and moving it from normal position upon opening movement of said money drawer, means for supporting a coin in position between said lug and presser bar, and means to release the supported coin upon actuation of said presser bar. 5

5. In a vending machine, a coin control including a coin chute, a release bar extending parallel to the chute and guided for longitudinal movement, said bar having a stop notch in the 10 edge adjacent the chute, a stop bar mounted to move transversely of the release bar to engage in and disengage from the notch, a lug on the stop bar extending into the chute at the side remote from the release bar, spring means normally 15 holding the stop bar in engagement in said notch, a presser bar opposite said lug and spaced from the lug at a slightly greater distance than the diameter of a coin to be used in the machine, said presser bar being mounted for movement 20 toward and from said lug, manually operable means for effecting operation of said presser bar, a spring held cut off normally closing the lower end of said chute, means on the release bar engageable with the cut off and moving the latter to open the chute upon movement of the release bar, a camming bar engageable with the stop bar to withdraw the stop bar from the notch upon movement and normally positioned to permit engagement of the stop bar in the notch, a 30 money drawer movable between open and closed positions, and means in the money drawer engaging the camming bar and moving it from normal position upon opening movement of said money drawer. 35

6. In a vending machine, a coin control including a coin chute, a release bar extending parallel to the chute and guided for longitudinal movement, said bar having a stop notch in the edge adjacent the chute, a stop bar mounted to move transversely of the release bar to engage in and disengage from the notch, a lug on the stop bar extending into the chute at the side remote from the release bar, spring means normally holding the stop bar in engagement in said notch, a presser bar opposite said lug and spaced from the lug at a slightly greater distance than the diameter of a coin to be used in the machine, said presser bar being mounted for movement toward and from said lug, spring means urging said presser bar away from the lug, pins projecting from the release bar, cam means on the presser bar wherewith said pins engage and arranged to force the bar toward the lug during initial movement of the presser bar and to permit movement of the presser bar away from the lug during further movement of the presser bar, plunger means operable to move said presser bar, means for supporting a coin in position between said lug and presser bar, and means to release the supported coin upon actuation of said presser bar.

7. In a vending machine, a coin control including a coin chute, a release bar extending parallel to the chute and guided for longitudinal movement, said bar having a stop notch in the edge adjacent the chute, a stop bar mounted to move transversely of the release bar to engage in and disengage from the notch, a lug on the stop bar extending into the chute at the side remote from the release bar, spring means normally holding the stop bar in engagement in said notch, a presser bar opposite said lug and spaced from the lug at a slightly greater distance than the diameter of a coin to be used in the machine, 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 5 said presser bar being mounted for movement toward and from said lug, spring means urging said presser bar away from the lug, pins projecting from the release bar, cam means on the presser bar wherewith said pins engage and arranged to force the bar toward the lug during initial movement of the presser bar and to permit movement of the presser bar away from the lug during further movement of the presser bar, 10 plunger means operable to move said presser bar, a spring-held cut off normally closing the lower end of said chute, and means on the release bar engageable with the cut-off and moving the latter to open the chute upon movement of the release bar.

15 8. In a vending machine, a coin control including a coin chute, a release bar extending parallel to the chute and guided for longitudinal movement, said bar having a stop notch in the edge adjacent the chute, a stop bar mounted to move transversely of the release bar to engage in and disengage from the notch, a lug on the stop bar extending into the chute at the side remote from the release bar, spring means normally holding the stop bar in engagement in said notch, a presser bar opposite said lug and spaced from the lug at a slightly greater distance than the diameter of a coin to be used in the machine, said presser bar being mounted for movement toward and from said lug, spring means 20 urging said presser bar away from the lug, pins projecting from the release bar, cam means on the presser bar wherewith said pins engage and arranged to force the bar toward the lug during initial movement of the presser bar and to permit movement of the presser bar away from the lug during further movement of the presser bar, 25 plunger means operable to move said presser bar, a camming bar engageable with the stop bar to withdraw the stop bar from the notch upon movement and normally positioned to permit engagement of the stop bar in the notch, a money drawer movable between open and closed positions, means in the money drawer engaging the camming bar and moving it from normal position upon opening movement of said money drawer, means for supporting a coin in position between said lug and presser bar, and means to release the supported coin upon actuation of said presser bar.

30 9. In a vending machine, a coin control including a coin chute, a release bar extending parallel to the chute and guided for longitudinal movement, said bar having a stop notch in the edge adjacent the chute, a stop bar mounted to move transversely of the release bar to engage in and disengage from the notch, a lug on the stop bar extending into the chute at the side remote from the release bar, spring means normally holding the stop bar in engagement in said notch, a presser bar opposite said lug and spaced from the lug at a slightly greater distance than the diameter of a coin to be used in the machine, said presser bar being mounted for movement toward and from said lug, spring means urging said presser bar away from the lug, pins projecting from the release bar, cam means on the presser bar wherewith said pins engage and arranged to force the bar toward the lug during initial movement of the presser bar and to permit movement of the presser bar away from the lug during further movement of the presser bar, 35 plunger means operable to move said presser bar, a spring-held cut-off normally closing the lower end of said chute, means on the release bar engageable with the cut-off and moving the latter to open the chute upon movement of the release bar.

40 10. In a vending machine, a coin control including a coin chute having a series of spaced lugs at one side and a presser bar at its other side mounted to move toward and from said lugs, stop bars mounted to move transversely of the chute and each carrying one of said lugs, spring means urging said presser bar away from the lugs, other spring means urging said lugs toward said stop bar, said lugs and stop bar being spaced to permit a series of like coins to be held in the chute with each coin loosely positioned between a respective lug and the presser bar, manually operable means to move the presser bar inwardly to cause the coins to move the stop bars and then to permit its outward movement to free said coins from the lugs, means for supporting a coin in position between said lug and presser bar, and means to release the supported coin upon actuation of said presser bar.

45 11. In a vending machine, a coin control including a coin chute having a series of spaced lugs at one side and a presser bar at its other side mounted to move toward and from said lugs, stop bars mounted to move transversely of the chute and each carrying one of said lugs, spring means urging said presser bar away from the lugs, other spring means urging said lugs toward said stop bar, said lugs and stop bar being spaced to permit a series of like coins to be held in the chute with each coin loosely positioned between a respective lug and the presser bar, manually operable means to move the presser bar inwardly to cause the coins to move the stop bars and then to permit its outward movement to free said coins from the lugs, setting means for engaging a selected number of the stop bars and moving them to inoperative positions, means for supporting a coin in position between said lug and presser bar, and means to release the supported coin upon actuation of said presser bar.

50 12. In a vending machine, a coin control including a coin chute having a series of spaced lugs at one side and a presser bar at its other side mounted to move toward and from said lugs, stop bars mounted to move transversely of the chute and each carrying one of said lugs, spring means urging said presser bar away from the lugs, other spring means urging said lugs toward said stop bar, said lugs and stop bar being spaced to permit a series of like coins to be held in the chute with each coin loosely positioned between a respective lug and the presser bar, a release bar having notches in one edge into which said stop bars may enter, said notches being of sufficient length to permit initial movement of the release bar with the stop bars engaged in the notches, said stop bars being withdrawn from the notches upon movement by the coins held between the lugs and presser bar, cooperating cam means on the release bar and presser bar for moving said presser bar toward the lugs and permitting its movement away from the lugs during initial movement of the presser bar, manual 55

ly operable plunger means for moving said presser bar, means for supporting a coin in position between said lug and presser bar, and means to release the supported coin upon actuation of 5 said presser bar.

13. In a vending machine, a coin control including a coin chute having a series of spaced lugs at one side and a presser bar at its other side mounted to move toward and from said lugs, 10 stop bars mounted to move transversely of the chute and each carrying one of said lugs, spring means urging said presser bar away from the lugs, other spring means urging said lugs toward said stop bar, said lugs and stop bar being spaced to permit 15 a series of like coins to be held in the chute with each coin loosely positioned between a respective lug and the presser bar, a release bar having notches in one edge into which said stop bars may enter, said notches being of sufficient length to permit initial movement of the release bar with the stop bars engaged in the notches, said stop bars being withdrawn from the notches upon movement of the coins held between the lugs and presser bar, cooperating cam means 20 on the release bar and presser bar for moving said presser bar toward the lugs and permitting its movement away from the lugs during initial movement of the presser bar, manually operable plunger means for moving said presser bar, setting means for engaging a selected number of the stop bars and 25 moving them to inoperative positions, a money drawer movable to open and close, cooperating elements on the setting means and money drawer, locking the setting means in position upon closing of the money drawer, means for supporting a coin in position between said lug and presser bar, and means to release the supported coin upon actuation of said 30 presser bar.
14. In a vending machine, a coin control including a coin chute having a series of spaced lugs at one side and a presser bar at its other side mounted to move toward and from said lugs, stop bars mounted to move transversely of the chute 40

and each carrying one of said lugs, spring means urging said presser bar away from the lugs, other spring means urging said lugs toward said stop bar, said lugs and stop bar being spaced to permit a series of like coins to be held in the chute with 5 each coin loosely positioned between a respective lug and the presser bar, a release bar having notches in one edge into which said stop bars may enter, said notches being of sufficient length to permit initial movement of the release bar with the stop bars engaged in the notches, said stop bars being withdrawn from the notches upon movement of the coins held between the lugs and presser bar, cooperating cam means on the release bar and presser bar for moving said presser 10 bar toward the lugs and permitting its movement away from the lugs during initial movement of the presser bar, manually operable plunger means for moving said presser bar, setting means for engaging a selected number of the stop bars and 15 moving them to inoperative positions, a money drawer movable to open and close, cooperating elements on the setting means and money drawer, locking the setting means in position upon closing of the money drawer, means for supporting a coin in position between said lug and presser bar, and means to release the supported coin upon actuation of said presser bar.

15. In a vending machine, a series of successively assemblable elements including a locking 30 collar forming the last element of the assembly, a latch holding said collar against removal and movable to release the collar, removable stop means restraining said latch from release movement, a money drawer movable between open 35 and closed positions, and cooperating means on the stop means and money drawer holding the stop means against removal upon closing of said drawer.
